UNITED STATES PATENT OFFICE.

JAMES SMITH AND DAVID E. BLAKE, OF ST. LOUIS, MISSOURI.

REFRIGERATOR.

SPECIFICATION forming part of Letters Patent No. 286,084, dated October 2, 1883.

Application filed June 20, 1883. (No model.)

To all whom it may concern:

Be it known that we, JAMES SMITH and DAVID E. BLAKE, of St. Louis, State of Missouri, have invented certain new and useful 5 Improvements in Refrigerators, of which the following is a full, clear, and exact description.

Our invention consists of an improved refrigerator constructed to cause perfect circulation of air from and to the ice box or chamber through the provision-chamber, and provided with means for regulating the current or rapidity of circulation, whereby economy in the consumption of ice may be effected.

15 Reference is to be had to the accompanying drawings, forming a part of this specification, in which similar letters of reference indicate corresponding parts in both the figures.

Figure 1 is a longitudinal sectional elevation of our new and improved refrigerator, taken on the line *x x* of Fig. 2; and Fig. 2 is a transverse sectional elevation taken on the line *y y* of Fig. 1.

A A are the inclosing-walls of the refrigerator. These are shown as plain wooden walls of single thicknesses of boards; but they might be made double and packed with non-conducting material, if desired.

B is an inclined partition of rods or slats, 30 which separates from the main provision-chamber C the ice box or chamber D, into which the ice is placed through the door E.

Above the provision-chamber C is formed, by the horizontal partition F and the top of 35 the refrigerator, the air-passage G, which leads back to the ice-box D, and is made the whole width of the provision-chamber.

Beneath the provision-chamber C is formed, by the slatted bottom H and the bottom of the 40 refrigerator, the air-passage J, which leads back to the chamber K beneath the ice-box D, and is also made the whole width of the provision-chamber. This chamber K, beneath the ice-box D, is formed by the slatted and perforated bottom L of the ice-box and the inclined 45 sheet-metal partition M, and in it is placed the receptacle or trough N for receiving the drip-water from the ice-box, which water is conducted away by the siphon-pipe O. The 50 inclined board P (also placed in the chamber K) serves to conduct the drip-water as it falls

from the bottom L of the ice-box to the trough or receptacle N, and this board is so arranged above the trough that cold air from the ice-box may pass between it and the trough down 55 into the chamber K below. From this chamber the cold air that thus descends from the ice-box will pass (provided the door Q is not closed) into the passage J beneath the provision-chamber, and from this passage will gradually find its way up through the slatted floor H into the provision-chamber C, as indicated by the arrows in the drawings. This cold air thus entering the provision-chamber, coming in contact with the provisions therein, will absorb heat, cooling the provisions, and becoming warmer and lighter from the heat taken up from the provisions will ascend and (provided the door R is not closed) will pass into 60 the passage G above the chamber C, through 65 which it will pass back into contact with the ice contained in the box D. From this contact with the ice the air will be reduced in temperature and will pass from the ice-box through the slatted partition B again into the 70 provision-chamber, to again exercise its cooling effect, and, becoming again warmer and lighter from contact with the provisions, will join (as indicated by the arrows) the current continually coming from the passage J, and 75 will pass with it again to the passage G, thence 80 back to the ice-box, to repeat the same course, and so on continually.

The valves O and R are provided for the purpose of regulating the current or rapidity 85 of circulation of air in the refrigerator, and these may be adjusted from the outside of the refrigerator, the former by the rod S, the latter by chain T, attached to them, respectively, so that by drawing outwardly upon the rod or 90 chain, or releasing them, the openings to the passage J G may be entirely closed or entirely opened, or more or less opened, to increase or diminish the circulation of air, as desired; and it is designed, in some cases, to attach the chain 95 T to the upper part, *a*, of the door U, so that whenever the door is opened it will close the valve R, stopping the circulation until the door is closed again, when the valve R will open. By properly manipulating these valves 100 great economy in the use of ice may be effected.

The door U to the provision-chamber C is

made in two parts, the upper part, *a*, and the lower part, *b*, which latter is wider than the upper part, and the upper part, *a*, is made to open independently of the lower part, *b*, so that in case a small article is to be placed in or removed from the refrigerator it may be passed through the upper part, *a*, without opening the lower part, *b*, thus avoiding the escape of large quantities of cold air from the refrigerator.

Having thus described our invention, we claim as new and desire to secure by Letters Patent—

1. In a refrigerator, the combination, with the outer casing, *A*, of the inner provision-chamber, *C*, having the valve *R*, the upper air-passage, *G*, lower air-passage, *J*, the valve *Q* and its operating handled rod *S*, ice-chamber *D*, separated from the provision-chamber by the inclined slatted partition *B*, having the

imperforate downward extension *M*, substantially as and for the purpose set forth.

2. In a refrigerator, the combination, with the outer casing, *A*, of the inner provision-chamber, *C*, having the valve *R*, the upper 25 air-passage, *G*, lower air-passage, *J*, the valve *Q* and its operating handled rod *S*, ice-chamber *D*, having the slatted bottom *L*, and separated from the provision-chamber by the inclined slatted partition *B*, having the imperforate downward extension *M*, the deflector or drain-board *P*, and the drip-receptacle *N*, having the siphon outlet-tube *O*, substantially as 30 and for the purpose set forth.

JAMES SMITH.
